[57] CLAIM

The ornamental design for a ball paddle for table game, as shown.

DESCRIPTION

FIG. 1 is a top plan view of a ball paddle for table game showing my new design;

FIG. 2 is a front side elevation thereof;

FIG. 3 is a reverse side elevation thereof;

FIG. 4 is a left end elevational view thereof;

FIG. 5 is a right end elevational view thereof; and

FIG. 6 is a bottom plan view thereof.
